UNITED STATES PATENT OFFICE.

CHARLES A. R. DIMON, OF LOWELL, MASSACHUSETTS, ASSIGNOR TO THE UNITED STATES CARTRIDGE COMPANY, OF SAME PLACE.

CARTRIDGE-SHELL-TRIMMING MACHINE.

SPECIFICATION forming part of Letters Patent No. 351,747, dated November 2, 1886.

Application filed September 6, 1886. Serial No. 212,806. (No model.)

To all whom it may concern:

Be it known that I, CHARLES A. R. DIMON, residing at Lowell, in the county of Middlesex and the Commonwealth of Massachusetts, have invented a new and useful Machine for Trimming Cartridge-Shells, of which the following is a true and complete specification.

My invention relates to machines for trimming or cutting off the ends of cartridge-shells; and it consists in certain new and useful constructions and combinations of the several parts thereof, substantially as hereinafter described and claimed.

In the drawings, Figure 1 is a side elevation of a machine for trimming cartridges provided with my improvements. Fig. 2 is a top plan view of the same. Fig. 3 is a section of the same on the line X X of Fig. 1. Fig. 4 is a detail view of the clutch or dog and my auxiliary cutter, showing the several positions of the latter. Fig. 5 is an end view of the clutch. Fig. 6 is a side view of a cartridge-shell before being trimmed or cut off in the machine. Fig. 7 is a side view of the same, partly in section, showing the shell when trimmed as heretofore in the machine. Fig. 8 is a side view of the same, partly in section, showing the shell when trimmed and operated upon by my auxiliary cutter.

A is the bed-plate of the machine, supporting at one end of it a standard, A', through which reciprocates back and forth the plunger a and the sleeve a'. Near the other end of the bed-plate are two standards or uprights, A'', supporting boxes at their upper ends, in which revolves the hollow mandrel M, driven by the pulley M' from a suitable counter-shaft. This mandrel has a bore through its center of sufficient diameter to allow the shell to pass through it, as shown in Fig. 4.

A post, a'', is fixed rigidly in the bed-plate, and has passing through it a screw, a'', tapped into it and resting against the sliding standard A', attached to the bed-plate. The upper end of the standard A'' fits into the groove a' around the mandrel M, and by setting up the screw a'' the standard A'' is made to take the thrust of the mandrel off from the boxes in the standards A'' A'' and relieve them.

B is an inclined guide or feeding trough, attached at its lower end to the block A', the

latter resting upon the bed-plate A. In the upper surface of this guide is a groove, b, which receives the shells sidewise and allows them to slide down into position to be operated upon 55 one after the other as they are taken away by the plunger a' from its lower end.

The plunger a' is round in cross-section and of the proper size to fit the inside of the cartridge-shell at its outer end, and it is fixed in 60 the plunger a and moves with it. These plungers are reciprocated longitudinally by any suitable and well-known mechanism, and the plunger a' passes the groove b in the feeding-plate B in proper relation thereto to enter the 65 lowermost cartridge-shell which has been fed downward through the groove and rests against an abutment opposite the lower end of the latter. The plunger a' is axially in line with the mandrel M, the latter provided on its inner end 70 with a dog for grasping the cartridge-shells. (Shown in detail in Figs. 4 and 5.)

On the mandrel M is placed a sliding sleeve, m, having a conoidal surface upon one end, over which the ends of the bent levers m' m' 75 are brought to bear, as shown. These levers are pivoted at m'', and carry upon their opposite ends the blocks m'', of segmental form, fitted on their inner surfaces to embrace the cartridge-shell shown at s, Fig. 5, in end view. 80 The sleeve m is moved longitudinally on the mandrel M by the lever m', which is pivoted at one end upon the vertical pivot m'', and embraces the sleeve m between the collars shown thereon at its other end. When the lever m' 85 is moved away from the plunger a', it draws the larger portion of its conoidal surface against the ends of the levers m' resting thereon, and closes the blocks m'' around the cartridge-shell, grasping the latter firmly. 90

The block A'' has a dovetail groove cut in its upper surface at right angles to the axis of mandrel M. In this groove is fitted a sliding plate, c, upon which is fixed the upright tool-post c', carrying the cutting-off or trimming tool c''. A set-screw, c'', in the top of the post serves to bind the tool in its slot therein in the usual manner. When the plate c is moved toward the mandrel M, the cutting-off tool c'' just passes the faces of the blocks m'' m'' of the 95 clutch, which grasps the shells. In the rear of tool-post c' another upright post, c'', is fixed in 100

plate c , having a hole through it parallel with mandrel M . Through this hole passes a screw-threaded shaft, c^5 , having nuts c^6 c^6 engaging with it on each side of post c^4 , to adjust 5 and clamp it in the post. This shaft carries in its end toward lever m^4 a roller, c^1 , pivoted in its bifurcated end, which roller bears against the edge of the lever. The edge of the latter is formed of a suitable cam shape where 10 the roller bears against it, so that as the tool c^2 and its carrying-plate c advances toward the mandrel M the roller will move lever m^4 away from tool c^2 , and thus close the clutch-blocks m^3 m^3 upon the shell, and hold it firmly while 15 the tool is cutting it off.

A vibrating lever, N , is pivoted to the bed-plate of the machine at n , and attached at one end by a pivot to the sliding plate c , the other end being moved by a suitable crank or other 20 mechanical equivalent working in slot n' . When the plunger a is moved forward, it carries its supplemental plunger a^5 through the lowermost shell, s , at the lower end of the groove b , to the closed end thereof, and carries 25 the shell forward between the blocks m^3 m^3 of the clutch. At the same time the tool-carrying plate c moves forward, gripping the shell in the clutch at the proper point, and cutting it off with tool c^2 .

30 So far as described the above machine is well known and in common use, and I have described it so far as is necessary to understand my improvement, further description of its mechanism being unnecessary to its being understood by those familiar with such machines. 35 When the tool c^2 cuts off the cartridge-shell, as shown in Fig. 7, it forms a slight burr on the cut-off end, projecting radially inward around the latter. This burr has proved troublesome in the subsequent processes of introducing the ball into the shell and crimping the latter around it, because it did not allow of that closeness of fit of the ball which is desirable. Even when removed, the thickness of 40 the metal at the edge cut off by tool c^2 is disadvantageous in crimping it into the metal of the ball, or a groove therein, to secure the shell and ball together.

45 My improvement consists in providing an auxiliary cutting-tool working in combination with the one before described, to cut away the burr formed by the latter while the shell is still held by the blocks m^3 m^3 , and to bevel out the edge of the shell at its cut-off end, as shown 50 at s^2 , Fig. 8, making it much thinner at its extreme outer edge, whereby it can be more perfectly crimped onto the ball, and allows the latter to enter it easier and with a tighter fit, and forms a more perfect junction between 55 them.

60 E is the auxiliary cutting-tool, pivoted to the face of block A' at e upon the bell-crank lever e' , to one arm of which it is attached. The other end of lever e' is attached to the lever e^6 by a pivot, e^7 , working loosely in a slot 65 in the latter and fixed in the end of the former to give the requisite play to the levers. Lever

e^2 is pivoted to a short standard attached to the bed-plate at e^4 , and has its other end made cam-shaped on the upper edge, as shown in Fig. 1. A spiral spring, t , attached to this short standard at one end and to the tool-carrying arm of lever e' at the other, draws the latter backward from the mandrel M . Another spiral spring, t' , between the free end of lever e^2 and the bed-plate, serves to lift that end of the lever to the proper position. 70

Attached to the sleeve a' , and sliding to and fro with it, is the lug or ear a^6 , through which a vertical screw-threaded hole is made, with which the screw-thread of the vertical rod a^7 engages. A check-nut, a^8 , on this rod serves 80 to bind it in the proper position in the ear. The lower end of the rod a^7 is bifurcated, and has the roller a^9 pivoted between its bifurcations in position to bear upon the upper cam-shaped edge of the lever e^2 , when the sleeve a' is drawn backward from the mandrel M a sufficient distance and depresses the lever at that end. This movement turns the bell-crank lever e' on its pivot and throws the tool E forward into the cut-off end of the shell at the proper angle to form the bevel s^2 on its edge, cutting off the burr on it formed by the tool c^2 in the operation, and leaving the shell as shown 95 in Fig. 8. During this process the shell has remained firmly gripped by the blocks m^3 m^3 and continues so gripped until the sleeve a' moves forward again to the position shown in Fig. 1. When the tool E is withdrawn, the plunger a^5 carries forward the next shell into the clutch, the sliding plate at the same time carrying back tool c^2 and releasing the finished shell, pushing the finished shell into the hollow of the mandrel beyond the clutch. The sliding plate c again advances, causing the clutch to grip the new shell and the tool c^2 to cut it off, while the sleeve a' goes backward, withdrawing plunger a^5 and bringing forward tool E , to bevel out the end of the shell. The shell 105 is thus trimmed and beveled at one operation, ready for crimping upon the ball. Fig. 4 shows the tool E in the act of beveling out the shell, and the position of the tool when withdrawn, in dotted lines. The tool is secured in 110 the arm of lever e' by means of the sleeve e^{10} , attached to the arm, into which the shank of the tool fits so as to slide in and out, and a set-screw, e^{12} , passing through the side of the sleeve and tapped therein. This construction 115 enables me to adjust the tool E accurately to its working position.

120 It is evident that the roller a^9 may be dispensed with and the rod a^7 be allowed to come directly in contact with lever e^2 , if desired. It is also evident that either of the springs t or t' may be dispensed with and the other used alone, if preferred; but I prefer to use both for greater certainty and quickness of action.

125 What I claim as new and of my invention is—

1. The combination of the revolving shell-gripping clutch provided with the radially-moving blocks m^3 m^3 , substantially conforming

to the exterior of the shell on their inner faces, and mechanism for moving the same in and out, the cutting-off tool c^2 , mounted on guide-ways and adapted to move past and in proximity to the face of said clutch transversely to the axis of rotation of the latter, and the reciprocating beveling-tool E, mounted upon a carrier, and adapted to enter the open end of the shell while the latter is held by the clutch 10 and trim or bevel off the inner part of the edge thereof, substantially as described.

2. The combination of the revolving shell-gripping clutch provided with the radially-moving blocks $m^3 m^3$, substantially conforming 15 to the exterior of the shell on their inner faces, and mechanism for moving the same in and out, the cutting-off tool c^2 , mounted on guide-ways and adapted to move past and in proximity to the face of said clutch transversely to the axis of its rotation, the pivoted lever e' , and the tool E, carried thereby, and adapted to enter the open end of the shell while the latter is held by the clutch and trim or bevel off 20 the inner part of the edge thereof, substantially as described.

3. The combination of the revolving shell-gripping clutch having the radially-moving blocks $m^3 m^3$, of proper conformation to embrace and hold the shell, and mechanism for 30 opening and closing the same, the reciprocating shell-carrying plunger $a' a^5$, the pivoted lever e' , and the tool carried thereby and adapted to enter the open end of said shell after the plunger is withdrawn therefrom and trim or 35 bevel off the inner part of the edge thereof, substantially as described.

4. The combination of the revolving shell-gripping clutch having the radially-moving blocks $m^3 m^3$, of proper conformation to 40 brace and hold the shell, and mechanism for opening and closing the same, the reciprocating shell-carrying plunger $a' a^5$, the tool E, the

pivoted lever e' , the pivoted lever e^2 , connected to lever e' , and the rod a' , connected to the plunger, and adapted to move the tool E forward within the shell by contact with lever e^2 45 on the backward movement of the plunger, substantially as described.

5. The combination of the revolving shell-gripping clutch having the radially-moving blocks $m^3 m^3$, of proper conformation to embrace the shell and hold it, and mechanism for 50 opening and closing the same, the reciprocating shell-carrying plunger $a' a^5$, the tool E, the pivoted lever e' , the pivoted lever e^2 , connected to lever e' , the rod a' , connected to the plunger, and adapted to move the tool E forward within the shell by contact with lever e^2 55 on the backward movement of the plunger, and the retracting-spring t or t' , connected to one 60 of said levers, substantially as described.

6. The combination of the revolving shell-gripping clutch having the radially-moving blocks $m^3 m^3$, of proper conformation to embrace and hold the shell, and mechanism for 65 opening and closing the same, the reciprocating shell-carrying plunger $a' a^5$, the pivoted lever e' , the tool E, carried thereby, and adapted to enter the open end of the shell after the plunger is withdrawn therefrom and trim or 70 bevel off the inner part of the edge thereof, and the retracting-spring t , connected to said lever, substantially as described.

7. The metallic cartridge-shell s, formed and prepared for crimping upon the bullet, substantially as described—that is to say, with the inner part of the edge thereof at its open end 75 trimmed or beveled off, substantially as described.
